(57) CLAIM

The ornamental design for a tool card, as shown and described.

DESCRIPTION

FIG. 1 is a front perspective view of a tool card showing my new design;

FIG. 2 is a front view thereof;

FIG. 3 is a right view thereof;

FIG. 4 is a left side view thereof;

FIG. 5 is a bottom view thereof;

FIG. 6 is a top view thereof; and,

FIG. 7 is a rear perspective view thereof.

A rear view is omitted since the rear view is a mirror image of the front view.
